Primary Examiner — Patricia A Palasik(74) *Attorney, Agent, or Firm* — Sarika Singh; McNeely, Hare & War LLP(57) **CLAIM**

The ornamental design an electric welding machine, as shown and described.

DESCRIPTION

FIG. 1 is a front view of an electric welding machine showing my new design;

FIG. 2 is a back view thereof;

FIG. 3 is a left view thereof;

FIG. 4 is a right view thereof;

FIG. 5 is a top view thereof;

FIG. 6 is a bottom view thereof; and,

FIG. 7 is a perspective view thereof.

The broken lines in the drawings depict unclaimed environmental subject matter.

1 Claim, 7 Drawing Sheets(56)
